UNITED STATES PATENT OFFICE.

VALENTIN JOSEPH MOHLER, OF BALTIMORE, MARYLAND, ASSIGNOR, BY MESNE ASSIGNMENTS, OF TWENTY-FIVE ONE-HUNDRED-AND-FOURTHS TO NANNIE T. HOOS, ONE ONE-HUNDRED-AND-FOURTH TO MABEL E. MOHR, TWENTY-FIVE ONE-HUNDRED-AND-FOURTHS TO RUTH B. WALTON, AND FOUR ONE-HUNDRED-AND-FOURTHS TO MARGUERITE G. SCHANBERGER, ALL OF BALTIMORE, MARYLAND; TWENTY-FIVE ONE-HUNDRED-AND-FOURTHS TO CALLIE E. MOORE, OF WASHINGTON, DISTRICT OF COLUMBIA; AND TWENTY-FOUR ONE-HUNDRED-AND-FOURTHS TO J. MARSH MATTHEWS, OF BALTIMORE COUNTY, MARYLAND.

DESIGN FOR A SAFETY-RAZOR-BLADE-STROPPER CASING.

Application filed November 10, 1921. Serial No. 514,398. Term of patent 14 years.

To all whom it may concern:

Be it known that I, VALENTIN JOSEPH MOHLER, a citizen of the United States, residing at city of Baltimore, State of Maryland, have invented certain new, original, and ornamental Design for a Safety-Razor-Blade-Stropper Casing, of which the following is a description, reference being had to the accompanying drawing, forming a part thereof.

Figure 1 is a front perspective; Figure 2 is a rear elevation; and Figure 3 is an end view, showing my new design.

I claim:

The ornamental design for a safety razor blade stropper casing, as shown.

In testimony whereof, I affix my signature.

VALENTIN JOSEPH MOHLER.
